CLAIM

I claim the ornamental design for a desktop scanner, as shown and described.

DESCRIPTION

FIG. 1 is an angular perspective view of a desktop scanner showing my new design;

FIG. 2 is a top view of the desktop scanner showing in FIG. 1;

FIG. 3 is a bottom view of the desktop scanner showing in FIG. 1;

FIG. 4 is a front view of the desktop scanner showing in FIG. 1;

FIG. 5 is a back view of the desktop scanner showing in FIG. 1;

FIG. 6 is a left side view of the desktop scanner showing in FIG. 1;

FIG. 7 is a right-side view of the desktop scanner showing in FIG. 1; and,

(Continued)

FIG. 8 is a perspective view of the desktop scanner showing in FIG. 1.
